UNITED STATES PATENT OFFICE.

GEORGE H. CLARK, OF CAMPELLO, MASSACHUSETTS, ASSIGNOR TO THE CLARK RELASTING AND SHOE-TREEING COMPANY, OF PORTLAND, MAINE.

BOOT-TREE.

SPECIFICATION forming part of Letters Patent No. 388,831, dated September 4, 1883.

Application filed March 27, 1888. Serial No. 268,621. (No model.)

To all whom it may concern:

Be it known that I, GEORGE H. CLARK, of Campello, county of Plymouth, State of Massachusetts, have invented an Improvement in 5 Jacks for Holding Boots or Shoes while being Operated upon, of which the following description, in connection with the accompanying drawing, is a specification, like letters on the drawing representing like parts.

10 This invention has for its object to construct a jack for holding boots or shoes while being operated upon—such, for instance, as while being treed or otherwise finished.

15 In accordance with this invention, the jack is composed of two similar parts or members forming the leg portion, one of the said parts being stationary or fixed to a rotatable holder, while the other part is pivoted to the stationary part, to be separated from the said part or member when desired. A suitable wedge-shaped block is interposed between the two parts or members, which is moved rearwardly by a treadle to separate one of the said parts or members from the other. Each part or member 20 has at its front end a pin, which receives upon it a last constructed in two parts—namely, a heel portion and a fore part—substantially as shown and described in an application for United States Letters Patent, Serial No. 268,620, filed by me March 27, 1888, one part upon each pin, so that as the parts or members of the jack are separated the heel portion and fore part will be separated to snugly fit, fit, or stretch the boot or shoe. The holder is 25 mounted upon a tilting or pivoted frame, so that the jack may be held at any desired inclination.

30 The drawing shows in side elevation a jack constructed in accordance with this invention for holding boots or shoes.

35 The main post or standard A has pivoted to it at its top, as by a bolt or pivot, 10, a frame composed of the top plate, B, and the side plate, B', which upon its upper side has a projecting open frame, B'. A holder, C, is fitted in the open frame B', and is free to be rotated or turned therein as desired.

40 The jack is composed of the members a and b, one of which, as a, is fixed to the rotatable

holder C, and the other, as b, is pivoted to the 50 said stationary member a, to be separated therefrom when desired. A rod, c, (see dotted lines,) passes through the holder C, said rod having at one end a wedge-block, c', which is interposed between the members of the jack, 55 while the other end of the rod has attached to it a grooved hub, c². A spiral spring (see dotted lines) surrounds the rod c between the wedge-block c' and that part of the stationary member a to which the member b is pivoted. 60 A bell-crank lever, d d', is pivoted within or to the top plate, one arm, d, of the said lever entering groove of the hub c², while the other arm, d', has attached to it the treadle-rod d², the latter being attached loosely at its lower end 65 to the pivoted treadle. By depressing the treadle T the treadle-rod d² is lifted, and by the bell crank lever the rod c and its wedge-block c' are moved rearwardly. The inclined side of the wedge-block bears upon the roller 70 b², placed within the movable member b, and as the said wedge-block is moved rearwardly the movable member b is separated. The jack 75 may be rotated with the holder c, and hence the necessity of grooving the hub c².

To lock the holder C in any desired position, a screw-threaded rod, e, is inserted in the frame B', which may be made to engage and hold the holder. The screw-rod is herein shown as forming a part of the crank-arm c'. 80 The front end of each member of the jack has a pivoted pin, i, (see dotted lines,) upon which pins the last which is contained in the boot or shoe is placed.

The last herein employed is composed of two 85 parts—namely, a heel portion, o, and a fore part, o'—substantially as shown and described in the application above referred to, so that one of the pins enters each member of the last.

In operating the jack the treadle is de- 90 pressed and the two parts or members of the jack thereby separated, as before described, and the two parts or members of the last will be thereby separated to snugly fit or stretch the boot or shoe, holding it while being treed 95 or otherwise operated upon. The treadle T will preferably have any suitable locking device to hold it in any desired position. The

frame or heel B B², tilting as described, permits the jack to be presented at any angle or inclination desired.

I claim—

- 5 1. In a jack for holding boots or shoes while being operated upon, the separable members *a b*, having the pins *i i* projecting from the ends thereof, combined with a two-part last adapted to be held upon the said pins, substantially as and for the purpose set forth.
- 10 2. In a jack for holding boots or shoes while being operated upon, the fixed member *a*, the pivoted member *b*, and means, substantially as described, for moving the member *b*, combined with the pins *i i*, projecting from the front end of the members *a b*, substantially as and for the purposes set forth.
- 15

3. In a jack for holding boots or shoes while being operated upon, the tilting head or frame, combined with the holder C, the separable members *a b*, attached thereto, the pins *i i*, projecting from the ends of the said members, and a suitable last therefor, substantially as described.

In testimony whereof I have signed my name 25 to this specification in the presence of two subscribing witnesses.

GEORGE H. CLARK.
